UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed February 1, 1923. Serial No. 616,275.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

The invention relates to sound-deadening 10 hoods or casings for typewriting machines. The present application is a division of my application, Serial No. 485,521, filed July 18, 1921.

The object of the invention is not only 15 to provide a casing with separated inner and outer walls forming an air-chamber therebetween for deadening the sound, but to further accentuate the sound-deadening character of the casing by the interposition, 20 between the two walls, of a partitioning wall or sheet of sound-deadening material, spaced from one or both of the inner and outer walls, and to so partition the wall structure by this sound-deadening sheet and other 25 means that the wall is made up of a series of cellular sections formed by vertically, longitudinally and transversely subdividing it.

Preferably, the sound-deadening partition 30 is spaced from both inner and outer walls of the casing so as to form two interior chambers. Where, as is usual, the casing-walls are of sheeting, the spacing may be effected by ribs on the opposed faces of the walls, 35 formed by elongated indentations in the walls; and the inner and outer walls and the partition may be held together and in place by rivets or pins passed through the ribs and through the partition, against which 40 the ribs bear.

Other features and advantages will hereinafter appear.

In the accompanying drawings,

Figure 1 is a view, in vertical cross-sectional side elevation, through the casing, from front to rear; the machine being indicated in dotted lines therein.

Figure 2 is a front view, partly cross-sectioned vertically of the body-part and 50 cover-part; the parts being disassembled.

Figure 3 is a top plan view of the casing and machine therein; the casing being partly in cross-section, and the cover-part having been removed.

55 The Underwood standard typewriting ma-

chine comprises a main frame 10, which may be supported upon a base 11 by supporting feet 12, the frame having a forward extension 13, in which are positioned banks of keys 14 to operate type-bars, not shown, and cause types carried by the type-bars to print against a platen 15, journaled in the end wall 16 of a platen-frame 17. The platen-frame forms part of a carriage 19 mounted for letter-feeding movement upon a front 60 rail 20 and a rear rail 21 fixed to the main frame. The carriage comprises various forwardly and downwardly extending operating levers, such as the carriage-release lever 22, the carriage-return finger-piece 23, and 65 the line-space handle 24, the carriage-release lever being guided in its movement by a bracket 25 fixed to the carriage-return finger-piece 23.

For deadening the sounds arising in the 75 typing operation, there is provided a hood or casing having a body-part 30 and a cover-part or cover 31 hinged at 32 to the body-part. The body-part comprises a rear wall 35, side walls 36, and a front wall in the 80 form of two end portions 37. These latter are spaced laterally to provide an opening through which the machine may be inserted into the casing, the machine being positioned 85 within the casing by abutments 40 fixed to the rear wall 35 and contacting with the rear posts of the main frame 10. When the machine is so positioned within the casing, the forward extension 13 projects forwardly 90 from and through the front wall of the casing. For closing all of the front openings not occupied by the forward extension, there is provided a front plate 41, which is mounted upon the portions 37 by means of hooks 95 42 projecting between said portions and engaging pins or studs 43 fixed to the portions 37, the hooks 42 being fixed to front slides 39 mounted upon the front plate 41 by means of studs 44 which guide the slides 39 100 in their upward and downward movement. The slides have finger-pieces 45 whereby they may be raised to release hooks 42 from pins 43, or lowered to cause the hooks to engage the pins.

The machine is then enclosed at the rear, sides and front, and, to enclose the machine at the top, there is provided the cover 31 having a rear wall 50, a top wall 51 provided with a transparent plate 52 to permit the interior of the casing to be viewed and make 105 110

the typing operation visible. The rear and top walls form a ceiling for the cover-part, while a front wall 53 terminates above the front plate 41, and side walls 58. A space 5 or slot is thus provided between the lower edge of wall 53 and the upper edge of plate 41, through which the various carriage-operating levers, heretofore mentioned, extend. To close all of the slot not actually occupied 10 by these levers, there is provided a set of co-operating cushions 54 and 55, each cushion comprising folds or loops of sound-deadening material, such as plush, felt, or soft leather. The two-ply margins of said loops 15 are clamped between bars 56 to form a unit, one of which is mounted on the front wall 53, so that cushion 54 extends downwardly, and the other of which is mounted on front plate 41, so that cushion 55 extends upwardly, the cushions contacting to close the slot. The cover may be raised by means of a finger-piece 57 and swung about hinge 32 to permit access to the machine.

It will be seen that the front plate 41, 25 with its attached cushion 55, extends upwardly to about the middle of the platen or on a line with the margin-stops of the machine. To permit greater access to these margin-stops and to the platen-rotating 30 knobs, as well as to other mechanism associated with the carriage, it is desirable that the front plate terminate some distance below the margin-stops. To maintain the slot in closed position, and still provide the 35 necessary space to allow access to the carriage mechanism, the front plate is provided with a hinged portion 72, which may be swung about a hinge 73 and lowered, but which is normally pressed upwardly into slot-closing position by springs (not shown).

To further deaden the sounds arising in the typing operation, both the body-part and the cover-part of the casing comprise walls spaced apart, so that sounds which are 45 transmitted by the inner wall must pass through the space between the walls before reaching the outer wall, thus effectively deadening the sounds. For this purpose, both the body-part and the cover-part each 50 comprise two similar members, one smaller than the other and fitted within the other, the inner member of each part being spaced from the outer member. Thus, the body-part comprises an inner member or inner 55 body-part 80 and an outer member or outer body-part 81, the inner member comprising an inner rear wall 83 (Figures 1 and 3), inner side members 84 (Figures 2 and 3), and inner front portions 85 (Figure 3), the 60 inner rear wall, side members and front portions being preferably separate plates riveted together. Similarly, the outer body-part 81 comprises an outer rear wall 86, outer side members 87, and outer front portions 88, the outer rear wall, side members 65

and front portions being preferably riveted together in a manner similar to the inner body-part. The inner body-part is provided on its upper edges with flanges 89 to overlie the corresponding upper edges of the outer body-part, and the outer body-part is provided on its lower edges with flanges 90, upon which rest the lower edges of the inner body-part. To assemble the body-part, therefore, it is only necessary to slide the 70 inner body-part downwardly into the outer body-part, until the flanges 89 rest upon the upper edges of the outer body-part, and the lower edges of the inner body-part rest upon the flanges 90 of the outer body-part. 75 To close the openings between the inner and outer body-parts at the front, along the front side edges, one of the body-parts (here shown as the outer body-part) may be provided with flanges 91 to overlie the side 80 edges of the other body-part.

The walls of the inner and outer parts are provided with co-operating similar, oppositely-positioned ribs or indentations 92, 90 which project inwardly from their inner opposite faces, and are arranged in vertical parallelism thereon. These oppositely-disposed ribs act not only to strengthen the walls, but also, when the wall structure is 95 assembled, the positions of the opposite ribs so coincide that they constitute a series of transverse vertical partitions, which divide the length of the wall-chamber into a series of closed, independent portions or discrete sound-deadening cells having air-chambers 100 that effect a sound-deadening of the typing operation. Fastening members 93 are passed through these walls to hold the walls together and are countersunk in the indentations. There are interposed between the 105 walls sheets 110 which may be composed of felt, cardboard, leather, or any other sound-deadening material, the sheets extending substantially parallel with the inner and outer members, as indicated in Figure 3. 110 These sheets are so interposed between the walls that the ribs or indentations 92 engage them on opposite sides, effectually closing each end of the sections formed between the partitioning ribs. While they 115 serve to space the opposite walls from each other, and likewise to keep the ribs from immediate contact with each other, for the prevention of sound-transmission, yet the sheets also serve as a means by which each 120 cell formed in the wall structure by the abutment of the oppositely-positioned ribs is divided longitudinally into sound-deadening air-chambers or pockets. They afford substantial obstruction to the transmission of sound through the casing, as well as through the air-space between the walls. 125 Similarly, the cover-plate 31 comprises an inner member 100 and an outer member 101, these members being similar in 130

shape, but the inner member being somewhat smaller so that it may fit within the outer member and be spaced therefrom. The inner member 100 comprises an inner rear and top wall, or ceiling, 102, and inner side walls 103, while the outer cover-part comprises an outer rear and top wall, or ceiling, 104, and outer side walls 105 (Figures 1 and 2). Both the inner and the outer cover-parts are cut out to provide the necessary opening for the transparent plate 52. The inner cover-part is provided, at its lower rear edge, with flanges 106, so that, when the inner and outer cover-parts are assembled, the inner cover-part need only be inserted upwardly within the outer cover-part, or the outer cover-part moved downwardly over the inner cover-part until the bottom edges of the outer cover-part rest upon the flanges 106. The inner and outer cover-parts are provided with indentations or corrugations 107 similar to the indentations 92 of the body-part, and are similarly fastened by bolts or rivets 108 passing through the indentations in the inner and outer walls of the cover-part and through sheets 111 of sound-deadening material.

It will be apparent from the foregoing description that there has been provided a sound-deadening casing having definite characteristics of construction and operation, by providing the outer walls with a series of oppositely-positioned, parallel ribs extending inwardly toward each other from the walls' inner faces. When the structure is assembled, it is made up of a series of independent sound-deadening chambered sections or discrete cells. The ribs divide the length of the wall structure into such sections by providing internal transverse partitions. In addition, each cell is divided longitudinally, into two opposite sections, by separating sound-deadening means, each section being provided with an air-chamber adjacent its walls. There is provided, therefore, a wall of few parts, and simple construction, composed of discrete cells closed at their opposite ends and made up of elements having varying degrees of sound conductivity. It will be obvious that this constitutes a structure having a high degree of resistance to the transmission of sound.

Variations may be resorted to within the scope of the invention, and portions of the improvements may be used without others.

Having thus described my invention, I claim:

1. A sound-deadening casing for a typewriting machine comprising hollow walls, each being formed with a series of discrete cells closed at their ends, each cell constituting a sound-deadening air chamber.

2. A sound-deadening casing for a typewriting machine comprising hollow walls,

each formed with means dividing the wall body into a series of discrete cells, each cell being subdivided by a longitudinal partition of sound-deadening material.

3. A sound-deadening casing for a typewriting machine comprising hollow walls, each formed with means integral with the wall body dividing the wall body into a series of discrete cells, each cell being subdivided with a longitudinal partition of sound-deadening material.

4. A sound-deadening casing for a typewriting machine comprising hollow walls, each formed with means integral with the wall body dividing the wall body into a series of discrete cells closed at their opposite ends, each cell being subdivided by a longitudinal partition of sound-deadening material.

5. A sound-deadening casing for a typewriting machine comprising hollow walls, each formed with means integral with the wall body dividing the wall body into a series of discrete cells closed at their opposite ends, each cell being subdivided by a longitudinal partition of sound-deadening material separating the walls throughout.

6. A sound-deadening casing for a typewriting machine comprising hollow walls formed with a series of discrete sound-deadening cells subdividing the wall body, said cells being closed at their opposite ends and subdivided by a longitudinal partition of sound-deadening material, forming an air chamber or pocket on each side of the sound-deadening material.

7. A sound-deadening casing for a typewriting machine comprising hollow walls, each formed with means integral with the wall body dividing the wall body into a series of discrete cells closed at their opposite ends, each cell being subdivided by a longitudinal partition of sound-deadening material separating the means dividing the wall body into cells.

8. A sound-deadening casing for a typewriting machine comprising hollow walls, each formed with means integral with the wall body dividing the wall body into a series of discrete cells closed at their opposite ends, each cell being subdivided by a longitudinal partition of sound-deadening fibrous material separating the walls.

9. A sound-deadening casing for a typewriting machine comprising hollow walls, each formed with means integral with the wall body opposite and projecting inwardly from the inner faces thereof dividing the wall body into a series of discrete cells closed at their opposite ends, each cell being subdivided by a longitudinal partition of sound-deadening material separating the walls.

10. A sound-deadening casing for a typewriting machine, said casing comprising inner and outer walls of sheet-material, a

- sheet of sound-deadening material set between the inner and outer walls, spacing elements formed by indentations in the inner and outer walls, in contact with the interior partition, whereby the inner and outer walls and the partition form two chambers, said indentations being substantially parallel and opposed to one another and formed unitary with the inner and outer walls, and means passing through the indentations and through the interior partition to hold the walls together.
11. A sound-deadening casing for a typewriting machine comprising hollow walls, each formed with means integral with the wall body opposite and projecting inwardly from the inner faces thereof dividing the wall body into a series of discrete cells closed at their opposite ends, each cell being subdivided by a longitudinal partition of sound-deadening material separating the walls and the opposite wall-partitioning means.
12. A sound-deadening casing for a typewriting machine comprising hollow walls, each formed with means integral with the wall body dividing the wall body into a series of discrete cells closed at their opposite ends, each cell being subdivided by a longitudinal partition of sound-deadening material separating the walls and the means dividing the wall body into cells.
13. A sound-deadening casing for a typewriting machine comprising inner and outer walls separated from each other and a partition of sound-deadening material spaced from the walls by a series of opposed ribs of substantially uniform cross-section integral with the walls projecting from the inner sides thereof, the sound-deadening material being between the opposed ribs, and means to hold said walls and sound-deadening material in assembled relation.
14. A sound-deadening casing for a typewriting machine comprising a body-part and a cover-part, each having walls composed of three substantially parallel members, two outer members and an intermediate member of fibrous sound-deadening material longitudinally partitioning said outer members from one another, the outer members having opposed ribs integral therewith and projecting inwardly therefrom separated by the intermediate member, and means to fasten the outer members and intermediate member in fixed relation, so that the wall structure comprises a series of discrete cells having air chambers.
15. A sound-deadening casing for a type-

writing machine, comprising inner and outer walls of sheet-material, ribs formed in the opposed faces of the two walls by elongated indentations thereof, and a partition between the two walls against which the ribs bear to form two chambers, the ribs in the inner and outer walls being unitary therewith, substantially parallel and opposed one to the other.

16. A sound-deadening casing for a typewriting machine, comprising inner and outer walls of sheet-material, ribs formed in the opposed faces of the two walls by elongated indentations thereof, a partition between the two walls against which the ribs bear to form two chambers, the ribs in the inner and outer walls being unitary therewith, substantially parallel and opposed one to the other, and means passing through the ribs and through the partition to hold the walls together.

17. A sound-deadening casing for a typewriting machine comprising a body-part and a cover-part, each having walls composed of a plurality of substantially parallel members, outer members and an intermediate member of fibrous sound-deadening material longitudinally partitioning said outer members from one another, the outer members having opposed ribs integral therewith and projecting inwardly therefrom separated by the intermediate member, and means to fasten the outer members and intermediate member in fixed relation and thereby subdivide the wall structure into a series of substantially similar discrete cells having air chambers formed by longitudinal and transverse partitions.

18. A sound-deadening casing for a typewriting machine comprising a body-part and a cover-part, each having walls composed of a plurality of substantially parallel plates, two outer plates and an intermediate partitioning plate of fibrous sound-deadening material, the outer plates having a series of opposed ribs of substantially uniform cross-section formed integral therewith, similarly projecting from the inner sides thereof inwardly, said partitioning plate being set between the opposed ribs in the outer plates, and means fastening the plates together in fixed relation so that the wall structure comprises a series of discrete cellular formations having air chambers.
